UNITED STATES PATENT OFFICE

JOSEPH P. THORLEY, OF SEBRING, OHIO, ASSIGNOR TO AMERICAN CHINaware CORPORATION, OF SEBRING, OHIO, A CORPORATION OF OHIO

DESIGN FOR A PLATE OR SIMILAR ARTICLE

Application filed December 13, 1930. Serial No. 37,972. Term of patent 3½ years.

To all whom it may concern:

Be it known that I, JOSEPH P. THORLEY, a citizen of the United States, residing at Sebring, in the county of Mahoning and State of Ohio, have invented a new, original, and ornamental Design for Plate or Similar Article, of which the following is a specification, reference being had to the accompanying drawing, forming part thereof.

Fig. 2, a perspective view showing the under side of the plate.

I claim:

The ornamental design for a plate or similar article, as shown.

JOSEPH P. THORLEY.
